UNITED STATES PATENT OFFICE.

GEORGE H. TANSLEY AND CHRISTIAN PFEIFFER, OF HARTFORD, CONNECTICUT, AS-SIGNORS TO COLT'S PATENT FIRE ARMS MANUFACTURING COMPANY, OF HARTFORD, CONNECTICUT, A CORPORATION OF CONNECTICUT.

AUTOMATIC MACHINE GUN.

Application filed September 24, 1923. Serial No. 664,465.

To all whom it may concern:

- Be it known that we, GEORGE H. TANSLEY and CHRISTIAN PFEIFFER, citizens of the United States, residing at Hartford, in the 5 county of Hartford and State of Connecticut, have invented certain new and useful Improvements in Automatic Machine Guns, of which the following is a specification, reference being had to the accompanying drawings, forming a part hereof.

The invention relates generally to automatic machine guns of that class in which the heavy recoiling parts, such as the barrel and barrel extension, are brought to rest gradually and without injurious shocks or stresses, by some form of buffer located within the breech casing, such as a liquid buffer or brake acting in the manner of a dash pot, for example, which buffer is made 15 adjustable to vary its action under the various conditions of operation to which such guns are liable.

The invention relates particularly to such guns in which the adjustable buffer rests 20 against the rear wall of the breech casing, and in which said rear wall comprises a plate transversely removable from the casing to permit withdrawal and inspection of the mechanism within said casing.

It is an object of the invention to provide 25 easily accessible means, preferably carried by the rear plate, for adjusting the buffer located within the breech casing of the gun without opening said casing, together with 30 means for indicating the amount of such adjustment on the outside of the casing.

A further object of the invention is the provision of devices whereby, in the removal 35 of the rear plate, the adjusting and indicating means carried by said rear plate is automatically disengaged from its operative relation with the buffer, thereby allowing of a rapid and easy removal of said rear plate and the parts carried thereby from the casing; it is a further object to provide means whereby the assembly of the rear plate and the parts carried thereby on the casing is facilitated.

These objects are attained by the mechanism illustrated in the accompanying drawings, in which:

Fig. 1 is a rear end view of a machine gun showing the invention applied thereto;

Fig. 2 is a left-hand side view of the rear

portion of the gun, parts being shown in 55 section;

Fig. 3 is a top view of said rear portion of the gun;

Fig. 4 is a side elevation of the rear portion of the gun showing the lower portion 60 in a central vertical longitudinal section, the adjusting and indicating means on the rear plate being shown in operative engagement with the buffer;

Fig. 5 is a side view similar to Fig. 4, but 65 showing the latch for the rear plate and the adjusting and indicating means in their inoperative position, preparatory to the upward removal of the rear plate;

Fig. 6 is a horizontal longitudinal section 70 through the rear portion of the gun casing, and through a tubular member therein, with a portion of the buffer tube broken away to show the groove in its rear wall, the section being taken on the line 6—6 of 75 Fig. 2;

Figs. 7, 8 and 9 show the combined indicating finger and adjusting arm, detached, respectively in a left-hand side view, in a 80 rear view and in a top view; and

Figs. 10, 11 and 12 show the rear plate latch, detached, respectively in a left-hand side view, in a front view and in a top view.

Similar numerals refer to similar parts 85 throughout the several views.

The breech casing of the gun to which the invention is shown applied comprises the side plates 1, 1, the top plate 2, the bottom plate 3 and the vertically removable rear plate 4, which is locked in its lower closed 90 position by the latch 5 having a forward projection which engages under the bottom plate 3.

The rear plate 4 has at its upper end a 95 forward projection which fits in a corresponding recess in the top plate 2, see Fig. 3, and said rear plate is provided with ribs or projections 4^a which fit corresponding vertical grooves in the side plates of the casing. Said rear plate is slid upwardly for 100 dismounting and downwardly for mounting it, and is kept in its seat by the latch 5 pivoted on the transverse pin 13 in the rear plate and held in its locking position with the forward projection thereon engaging under the rear end of the bottom plate 3 of the casing by the spring 14. An upward projection 5^b on said latch limits the 105 forward movement of the rear plate.

ward movement of its lower end when the rear plate is withdrawn from the casing, and a curved finger piece 5^e forms an extension of the lower arm of the latch to facilitate the operation thereof.

Within the breech casing are mounted the recoiling parts of the mechanism (not shown), the recoil of which is cushioned by any suitable form of buffer or brake, such as the liquid buffer represented by the cylindrical tube 8 resting against the rear plate of the casing and rotatably mounted in the tubular member 9 fitting the lower rear portion of said casing.

For adjusting said buffer, which may comprise some form of dash pot device, (such as is fully disclosed for example in the application of J. M. Browning, Serial Number 654,955, filed July 31, 1923,) the rotatable tube 8 is provided with a transverse groove 8^a in its integral rear wall; a corresponding rib 10^a on the forward end of a shaft 10 is adapted to extend into this groove. Said shaft is mounted in the rear plate and projects outside said plate at its rear end, where it is provided with a combined adjusting arm and indicating finger 12, which is connected with said shaft by any suitable means, such as a transverse pin.

By this construction it will be obvious that the shaft 10 can be rotated manually to adjust the rotatable buffer tube 8 by simply grasping the adjusting arm 12 and rotating it the required amount.

In order to permit the upward removal of the rear plate 5, it is necessary to withdraw the rib 10^a on the shaft 10 from the groove 8^a in the buffer tube 8; to allow such withdrawal, the shaft 10 is mounted in the rear plate so as to have endwise movement. The shaft is yieldingly held in its inner operative position by a spring 11 coiled about it and bearing at its forward end against a collar on the shaft, and at its rear end against a shoulder on the rear plate, see Figs. 4, 5 and 6. By moving the shaft rearwardly against the tension of the spring 11 to the position shown in Fig. 5, the rear plate 4 can be upwardly withdrawn, assuming that the rear plate latch 5 has been disengaged from the bottom plate 3.

By our invention, this rearward movement of the shaft 10 is effected automatically in the act of removing the rear plate. A convenient manner of attaining this end is to provide co-operating devices on said adjusting arm 12 and the rear plate latch 5, so that, when the latch 5 is moved rearward to free the forward projection thereon from the bottom plate 3, the adjusting arm 12 and the connected shaft 10 will be simultaneously moved rearward, thereby withdrawing the rib 10^a on the forward end of said shaft from the groove 8^a in the buffer tube.

Such devices may comprise a cam surface 5^a on the rear face of the latch 5, see Figs. 4 and 10, which surface is in position to engage the lower slightly rounded edge of a laterally widened sector-shaped forward portion of the arm 12, said portion forming wings 12^d, see Figs. 8 and 9, projecting at each side of the central knurled portion 12^c of the arm, which is adapted to be grasped by the hand of the operator. Said wings 12^d project laterally a distance sufficient to insure that, in all operative positions of the adjusting arm 12, some part of the lower rounded edge of said sector-shaped portion will be located opposite said latch 5, whereby the cam surface on the latch may engage said rounded edge of the arm 12 to cam it back regardless of the position of adjustment of the parts within their operative limits.

The means for indicating the amount of the adjustment of said buffer may comprise graduations and an index co-operating with said graduations; in the form of our invention shown, an upward projecting finger 12^b on the arm 12 serves as an indicating finger and is preferably provided with an index or notch 12^a which co-operates with suitable opposed fixed graduations, see Fig. 1, to indicate the amount of the adjustment.

To remove the rear plate, the operator pulls rearwardly on the finger piece 5^e of the latch 5 to withdraw the forward projection on said latch from beneath the bottom plate 3, and during such rearward movement, the cam surface 5^a on said latch engages the lower rounded edge of the sector-shaped forward portion of the adjusting arm 12 and thereby moves said arm and the connected shaft 10 rearwardly against the tension of the spring 11, thus withdrawing the rib 10^a on said shaft from the groove 8^a in the buffer tube 8, then the rear plate may be upwardly withdrawn from the casing.

To facilitate the re-assembly of the rear plate, suitable provision is made to move the shaft 10 rearward automatically during the downward sliding movement of the rear plate in mounting it. To this end, the upper edge of the tubular member 9 is rounded over as shown at 9^a, so that, when the rib 10^a encounters said rounded edge the rib is cammed back and the downward movement of the plate 4 is continued, until the bevel on the under side of the forward projection 5^d of the latch 5 engages the bottom plate 3 and automatically moves the latch rearwardly; by beveling the top of the end of the plate 3 this action is facilitated. When the plate 4 and the latch reach the lowest position, the forward projection 5^d of the latch will reengage the bottom plate under the action of the spring 14, and at the same time the rib 10^a of the shaft 10 will under the action of spring 11 reenter the groove 8^a.

in the buffer tube, when the rib and the groove coincide. If, however, the shaft 10 or the tube 8, have been rotated relatively from the position they occupied before the removal of the rear plate, then the rib 10^a and the groove 8^a may not extend lengthwise in the same direction when the rear plate is reassembled; by simply rotating the shaft 10 until said rib and said groove again 10 extend in the same direction, the rib will be automatically moved into said groove by the action of the spring 11.

The adjusting and indicating mechanism mounted on the rear plate, is, for convenience of manufacture, carried by a separate piece 4^b which is secured to the rear plate proper by suitable means, such as the screws 7, see Figs. 1 and 2, but it is obvious that this piece 4^b might be an integral part 20 of the rear plate 4.

While we have herein described in detail a specific embodiment of our invention, we do not wish to limit ourselves to the particular construction or arrangement of parts 25 shown and described, as obvious modifications will occur to those skilled in the art.

What we claim and desire to secure by Letters Patent is:

1. A machine gun comprising a breech casing having a rear plate, a rotatably adjustable member resting against said rear plate, a shaft for adjusting said member mounted in said rear plate and means for indicating the amount of the adjustment 35 associated with said shaft.

2. A machine gun comprising a breech casing having a rear plate, a rotatably adjustable buffer member resting against said rear plate and having a groove in its rear 40 surface, a shaft mounted in said rear plate and having a rib on its forward end extended into said groove, and means outside said casing for rotating said shaft and thereby adjusting said member.

3. A machine gun comprising a breech casing having a transversely removable rear plate, a rotatably adjustable buffer tube resting against said rear plate and having a groove in its rear surface, a rotary member having a corresponding rib at its forward end for engagement into said groove, said rotary member being mounted in said rear plate, resilient means for holding said member in its forward position with its rib engaging said groove, and means outside said casing whereby said member may be rotated to adjust said buffer tube and moved endwise against the tension of said resilient means to withdraw said rib from said 55 groove, thereby permitting removal of the rear plate when desired.

4. In a machine gun, the combination of a breech casing having a transversely removable rear plate, an adjustable member inside 60 said casing, and means carried by said rear

plate and normally connected with said member for adjusting it, said means being constructed and arranged to be automatically disconnected from said adjustable member upon removal of said rear plate. 70

5. In a machine gun, the combination of a breech casing having a transversely removable rear plate, a rotatably adjustable member in said casing and having its rear end resting against said rear plate, and means carried by said rear plate and normally connected with said member for adjusting it, said means being constructed and arranged to be automatically disconnected from said adjustable member upon removal 80 of said rear plate.

6. In a machine gun, the combination of a breech casing having a transversely removable rear plate, a rotatably adjustable buffer member in said casing and resting 85 against said rear plate, means carried by said rear plate and normally operatively connected with said member for adjusting it, a latch for locking said rear plate in assembled position, and devices whereby 90 the movement of said latch to release the rear plate automatically disconnects said member and said means to permit withdrawal of the rear plate from the casing.

7. In a machine gun, the combination of a breech casing having a transversely removable rear plate, a longitudinally extending member adapted to be rotatably adjusted and resting against said rear plate, means carried by said rear plate and normally in 100 operative engagement with said member for adjusting the same, and means for automatically breaking said operative engagement upon removal of the rear plate comprising a device for locking said rear plate in its 105 assembled position.

8. In a machine gun, the combination of a breech casing having a transversely removable rear plate, a rotatably adjustable member in said casing and resting against 110 said rear plate, said member having a groove in its rear surface, a rotary device carried by said rear plate and having a rib at its forward end entering said groove whereby rotation of said device causes corresponding rotation of said member, and means for automatically withdrawing said rib from said groove in the removal of said rear plate from the casing. 115

9. In a machine gun, the combination of a breech casing having a transversely removable rear plate, a rotatably adjustable member in said casing and resting against said rear plate, said member having a groove in its rear surface, a shaft carried by said rear plate and having a corresponding rib at its forward end entering said groove, means yieldingly holding said shaft in its forward position with its rib in said groove, and means secured to the outer end of said 120 125

shaft whereby the same may be rotated to adjust said buffer member and automatically move endwise in the removal of the rear plate against the tension of said yielding means to withdraw said rib from said groove.

10. In a machine gun, the combination of a breech casing having a transversely removable rear plate, a latch pivotally mounted in said rear plate for holding the same in its assembled position, a rotatably adjustable member in said casing and resting against said rear plate, said member having a groove in its rear surface, a rotary shaft 65 carried by said rear plate and having a corresponding projection at its forward end extending into said groove, said shaft having also an endwise movement, and means whereby the movement of the latch to release said rear plate automatically moves said shaft endwise to withdraw said projection from said groove, thereby facilitating the removal of the rear plate.

11. In a machine gun, the combination of a breech casing having a transversely removable rear plate, a latch carried by said rear plate for locking it in assembled position, a rotatably adjustable member in said casing and resting against said rear plate, a rotary shaft carried by said rear plate and operatively connected with said adjustable member, said shaft having also an endwise movement to break said connection, a sector shaped arm secured to said shaft, 80 said arm and said latch having co-operative cam surfaces, whereby movement of the latch to release the rear plate automatically moves said shaft endwise to break said connection for all operative positions of said arm.

12. In a machine gun, the combination of a breech casing having a transversely removable rear plate, a latch for locking said rear plate in assembled position, a rotatably adjustable member in said casing and resting against said rear plate, said member having a groove in its rear surface, a shaft carried by said rear plate and having a rib in its forward end entered into said groove whereby rotation of the shaft causes rotation of said member, said shaft also having endwise movement to withdraw said rib from said groove, an arm secured to said shaft carrying an arcuate cam surface, and 95 a cam surface on said latch for co-operation with said arcuate cam surface in any operative position of said arm, whereby movement of the latch to release said rear plate automatically moves said shaft endwise for withdrawing said rib from said groove.

13. In a machine gun, the combination of

a breech casing having a transversely removable rear plate, a latch for locking said rear plate in assembled position, a rotatably adjustable member in said casing and resting against said rear plate, combined adjusting and indicating means operatively connected with said member and constructed and arranged to be automatically disconnected therefrom upon the movement of 70 said latch to release said rear plate.

14. In a machine gun, the combination of a breech casing having a transversely removable rear plate, a latch for locking said rear plate in assembled position, a rotatably adjustable member in said casing and resting against said rear plate, said member having a groove in its rear surface, a shaft carried by said rear plate and having a corresponding rib extended into said groove, a combined adjusting and indicating arm secured to said shaft, and a connection between said arm and said latch whereby the shaft is moved endwise to withdraw said rib from said groove when the latch is 80 moved to release the rear plate.

15. In a machine gun, the combination of a breech casing, having a transversely removable rear plate, an adjustable member resting against said rear plate, means carried by said rear plate for adjusting said member from the outside of the casing, and means whereby in the removal of said rear plate, said adjusting means is automatically moved to disengage it from said member, and means permitting the automatic re-engagement of said parts upon the re-assembly of said rear plate.

16. In a machine gun, the combination of a breech casing having a transversely removable rear plate, an adjustable member resting against said rear plate and having a groove in its rear surface, a shaft carried by said rear plate, said shaft being yieldingly held in a forward position with a rib thereon extending into said groove, and means whereby, upon the removal of the rear plate, said shaft is automatically moved endwise to withdraw said rib from said groove, and means whereby said shaft is automatically moved rearwardly to allow the full insertion of said rear plate in its seat in the casing and to permit the automatic re-engagement of said rib and said groove.

This specification signed and witnessed this 14th day of September, A. D. 1923.

GEORGE H. TANSLEY.
CHRISTIAN PFEIFFER.
